UNITED STATES PATENT OFFICE.

EDWARD C. OBERMEYER, OF NESSEN CITY, MICHIGAN.

GAS DEVICE.

1,189,994.

Specification of Letters Patent.

Patented July 4, 1916.

Application filed March 11, 1916. Serial No. 83,599.

To all whom it may concern:

Be it known that I, EDWARD C. OBERMEYER, a citizen of the United States, residing at Nessen City, in the county of Benzie and State of Michigan, have invented a new and useful Gas Device, of which the following is a specification.

The device forming the subject matter of this application is adapted to be employed 10 on a gas stove or a gas lamp for the purpose of igniting the gas at the burner automatically, the construction being such that when the flame is extinguished accidentally at the burner, and when a valve in the supply pipe 15 to the burner is in an open position, the gas will be ignited automatically at the burner.

Specifically, the invention aims to provide 20 novel means whereby a plurality of electrical terminals and conducting members may be held in operative relation to the burner.

It is within the province of the disclosure 25 to improve generally and to enhance the utility of devices of that type to which the present invention appertains.

With the above and other objects in view which will appear as the description proceeds, the invention resides in the combination and arrangement of parts and in the 30 details of construction hereinafter described and claimed, it being understood that changes in the precise embodiment of the invention herein disclosed can be made within the scope of what is claimed, without departing 35 from the spirit of the invention.

In the accompanying drawings:—Figure 1 shows in side elevation, a burner whereunto the device forming the subject matter of this application has been attached, parts 40 appearing in section; Fig. 2 is a sectional view of the carrying member, the circuits being indicated diagrammatically; Fig. 3 is a fragmental section showing the slide and parts associated therewith; and Fig. 4 is a 45 diagrammatic view wherein the device forming the subject matter of this application is shown in operative relation to a burner of the type used on a gas stove.

In the accompanying drawings, the number 50 1 indicates a gas pipe in which is journaled a rotary valve 2 adapted to control the flow of gas through the pipe 1. Assembled with the pipe 1 is an insulating casting 3 bearing a terminal 4 adapted to coact 55 with a switch blade 5 on the valve 2. The construction is such that when the valve 2

stops the flow of gas through the pipe 1, the blade 5 will be out of contact with the terminal 4. The numeral 6 indicates a burner of any desired sort, communicating 60 with the gas pipe 1.

Mounted on the pipe 1 and held thereto by a clamp 7 is a bracket 8 supporting an insulating carrying member 9. Mounted transversely in the carrying member 9 is a 65 terminal 10 provided at its outer end, as shown at Fig. 3, with a socket 11 in which is mounted to reciprocate, transversely of the socket, a slide 12 having an opening 14 disposed opposite to a seat 15 fashioned in 70 the end of the terminal 10. A spring 16 is engaged with the seat 15 and with the opening 14. In the slide 12 is formed a notch 17 defining spaced shoulders 18 and 19.

Mounted in the insulating carrying member 75 9 is a conducting terminal 20 to which is attached a thermo-expansible arm 21 terminated in a rectangularly disposed end 22, the arm being cruciform in cross section, in order that it may present a large amount 80 of surface to the burner 6. The end 22 of the arm 21 projects into the socket 11 and enters the notch 17 in the slide 12. That side of the end 22 of the arm 21 which is adjacent the shoulder 19 of the slide 12 85 carries an insulating piece 23.

The numeral 24 denotes a third terminal located between the terminals 10 and 20 and mounted in the member 9.

The numeral 27 indicates a conductor one 90 end of which is attached to the terminal 20, the other end of which is attached to the terminal 10. Interposed in the conductor 27 is a source of electrical energy indicated at 25. Also interposed in the conductor 95 27 is the primary winding 26 of an induction coil. The secondary winding of the induction coil is shown at 28. From one end of the winding 28 a conductor 29 leads to the terminal 24. A condenser 29 is interposed in the conductor 29. From the other end of the winding 28, leads a conductor 30 which is connected to the conductor 27. Interposed in the conductor 27 is an interrupter 31. 100 105

The electrical circuits above outlined are not insisted upon, and may be changed without jeopardizing the utility of the invention.

In practical operation, when the valve 2 110 is turned to cut off the flow of gas through the pipe 1, the switch blade 5 is out of

contact with the terminal 4. The end 22 of the arm 21 bears against the shoulder 18 of the slide 12. If the valve 2 is now manipulated to permit the passage of gas 5 through the pipe 1, then the blade 5 engages the terminal 4 and there is established a circuit comprising the battery 25, the primary winding 26, the conductor 27, the terminals 10 and 20, the arm 21, its end 10 22, the slide 12 (as shown in Fig. 3), the socket 11 and the spring 16. A current is induced in the second winding 28 and there is established a circuit comprising the conductor 29, a part of the conductor 27, the 15 terminal 24, the arm 21 and the terminal 20. A spark will now jump from the terminal 24 to the arm 21 and the gas burner will be ignited. Due to the heat of the flame at the burner 6, the arm 21 will expand thus 20 moving the end 22 of the arm out of contact with the shoulder 18. The circuit including the primary winding 26 therefore will be broken and no spark will jump from the terminal 24 to the arm 21. If the flame at 25 the burner 6 is extinguished accidentally, then the arm 21 will contract until the end 22 of the arm engages the shoulder 18 of the slide 12, whereupon the gas will be ignited automatically.

30 The reason for providing the slide 12 is in order that the arm 21 may expand, the insulating piece 23 on the end 22 of the arm engaging the shoulder 19 on the slide, and consequently the circuit is not closed. The 35 function of the spring 16 is to restore the slide 12 to the position of Fig. 3, should the slide be carried to the right, in Fig. 3, when the arm 21 expands.

The device forming the subject matter of 40 this application need not be employed in connection with an illuminating burner as shown in Fig. 1. In Fig. 4, the structure is shown diagrammatically in operative relation to a burner 32 which may constitute a 45 part of a heater.

Having thus described the invention, what is claimed is:—

1. In a device of the class described, a support; a first terminal carried by the support; a second terminal carried by the support; a third terminal carried by the support and located between the first and second terminals; a thermo-expansible arm connected with the first terminal and adapted to coact with the second terminal, the third terminal being disposed in close relation to the arm.

2. In a device of the class described, a support; a first terminal carried by the support; a second terminal carried by the support; a third terminal carried by the support and located between the first and second terminals; a thermo-expansible arm connected with the first terminal, the third terminal being disposed adjacent the arm; and a slide 55 mounted to reciprocate on the second terminal, the end of the arm being interengaged with the slide.

3. In a device of the class described, a support; a first terminal carried by the support; a second terminal carried by the support; a third terminal carried by the support and disposed between the first and second terminals; a thermo-expansible arm connected with the first terminal; a slide 75 mounted to reciprocate on the second terminal and provided with spaced shoulders between which the arm is located; an insulating element carried by the arm and adapted to coact with one shoulder; and spring 80 means for controlling the movement of the slide.

In testimony that I claim the foregoing as my own, I have hereto affixed my signature in the presence of two witnesses.

EDWARD C. OBERMEYER.
